HYDRAULIC DEBARKER HAVING AUTOMATICALLY CONTROLLED LOG SPEED AND NOZZLE SPACING, STROKE AND SPEED

Ernest C. Shaw, Orville C. Frank, and Clifford C. Jackson, Milwaukee, Wis., assignors to The Filer & Stowell Company, Milwaukee, Wis., a corporation of Wisconsin

Application August 8, 1957, Serial No. 677,027

10 Claims. (Cl. 144—208)

This invention relates to improvements in hydraulic log-debarking apparatus for debarking logs of various sizes.

Apparatus of this type employs movable nozzles supplied with water under high pressure to debark a log as it is advanced past the apparatus. The means for moving the nozzles with respect to the log for effective debarking thereof and the control means to adjust the apparatus for debarking logs of various sizes have been complicated and expensive. Furthermore, such apparatus has been inefficient because an undue amount of water has been wasted.

It is the primary object of this invention, therefore, to provide a hydraulic log debarker of simplified design with improved reliability and increased efficiency at reduced cost.

Another object is to provide a debarker with a simplified control means of novel design to automatically adjust the apparatus for debarking logs of various sizes.

The apparatus includes a frame having a debarking station through which logs of various diameters are translated longitudinally along a fixed plane. A pair of oppositely facing nozzles are movably mounted on opposite sides of the logs traveling through the debarking station and supplied with liquid under high pressure. The nozzles are simultaneously reciprocated in straight-line movement so that the liquid jets will move transversely over the surface of the log from diametrically aligned opposite directions.

Control means including a log-diameter-sensing element is provided to automatically adjust: (1) the spacing of the nozzles; (2) the amplitude of their reciprocal movement from such fixed plane; (3) the speed of log travel; and (4) the speed of nozzle travel depending upon the diameter of the log.

Other objects and advantages of this invention will be apparent from the detailed description that follows and the illustrations in the accompanying drawings, wherein:

Fig. 1 is a partially schematic side elevation of a debarking apparatus embodying the present invention;

Fig. 2 is a fragmentary view in side elevation with one wall of the frame removed to show the mechanism for translating logs of various diameters longitudinally through a debarking station;

Fig. 3 is a fragmentary perspective (partially schematic) view showing the mechanism for reciprocating the nozzles and controlling such nozzle movement for debarking logs of various sizes;

Fig. 4 is a fragmentary end elevation showing the actuating and control mechanisms for the nozzles;

Fig. 5 is a view similar to Fig. 4 showing the actuating

2

and control mechanisms adjusted for logs of maximum diameter; and

Fig. 6 is a view similar to Fig. 5 showing the mechanism adjusted for logs of minimum diameter.

While the invention is shown and described as apparatus for debarking logs, it should be understood that the invention may be embodied in any device wherein treatment of elongated objects with a liquid jet is contemplated.

The machine comprises a debarking station 10 enclosed by a housing or frame 11 for the prevention of splash and a conveyor mechanism 13 for translating logs 12 and 14 (Fig. 2) of various diameters longitudinally through the debarking station. The conveyor may be of any known type having a trough-like table or bed on which a cylindrical object will be supported in a stable position during the debarking operation. If a stationary trough or bed is used suitable known means may be used to push or pull the object along the bed or trough but, in the preferred form illustrated in the drawings, the conveyor mechanism 13 comprises a plurality of fluted or spiked V rolls 16 mounted for rotation on shafts 17 journaled in the frame 11 and an endless chain 18 drivingly connecting spur gears 15 on the shafts 17. The conveyor mechanism 13 is driven (Fig. 1) by a motor 19 through a variable-speed transmission 20, drive shaft 21, chain drive 22, shaft 23, and bevel gears 24 which drive the shaft 17 farthest to the left (Fig. 2) to translate logs 12 and 14 of various diameters longitudinally from right to left (Fig. 2) along a substantially fixed horizontal plane 25 (at lowermost point of peripheral surface of the logs).

A plurality of plate steel baffles 26, 27, 28 and 30 are pivotally mounted at one end above the conveyor and connected to a plurality of dashpot cylinders 32 mounted on the outside of the frame. The free ends of the baffles ride on the top surface of the logs to hold them firmly in position while passing through the machine and also help to keep the spray and bark from spouting out of the ends of the frame housing. As will be explained more fully hereinafter, the baffle 28 is also utilized in the control mechanism of the machine.

The logs are debarked by the action of hydraulic jets upon the peripheral surfaces thereof. These hydraulic jets will remove bark over a substantial area surrounding the point of impact but if all bark is to be removed from a log passing on a conveyor it will be necessary either to provide a great many jets or to move the point of impingement of one or more jets circumferentially with relation to the log surface as the log moves longitudinally without rotation. The present invention contemplates the use of a smaller number of jets than would be required to remove all bark without relative circumferential motion, and to do so by moving the points of impact of these jets transversely in reciprocal straight-line motion as the log passes longitudinally through the debarking station.

The debarker is equipped with two pressure nozzles 34 preferably of stainless steel with apertures machined to eject a flat stream of water or other suitable liquid. The nozzles are threaded on nozzle connectors 36 which in turn are securely mounted in crossheads 38 with the nozzles directed so that the flat sides of the jets are substantially parallel to the longitudinal axis of the logs and so that the jets are parallel to the substantially fixed hori-

zontal plane 25 along which the logs travel. The nozzles are supplied (Fig. 1) with water or other liquids under high pressure from a header 40 through piping 42 and flexible conduits 44. The mounting of the nozzles 34 and connectors 36 directly in the movable crossheads 38 eliminates many of the support problems generally encountered in movably mounting nozzles supplied with liquids under high pressure.

The nozzles 34 and connectors 36 which extend into the interior of the frame 11 through openings 33 in the sides thereof are actuated in a straight-line reciprocal movement by the crossheads 38 slidably mounted in vertical guideways 46 which in turn are slidably mounted for movement toward and away from the logs on the outside of the frame opposite one another.

The nozzles 34 mounted in the crossheads 38 are reciprocated vertically from a point in plane 25 at the bottom of the logs by a pair of counterbalanced lever arms 48 and 50 connected to the crossheads 38 by connecting rods 52. The counterbalanced lever arms are driven by a drive shaft 54 which is in turn driven by a drive lever 56 fixed to the drive shaft and connected to a fixed-throw crank 58 on a shaft 62 by a connecting rod 60, a link 63 and a crosshead 61 slidably mounted on the drive lever 56. The fixed-throw crank 58 is driven by the motor 19 from the shaft 23 by means of a chain drive 68 connected between sprocket wheels 66 and 64 on the shafts 23 and 62, respectively. The counterbalanced lever arm 50 is driven by the lever arm 48 through a connecting link 70 and pivots on a shaft 72 as the lever arm 48 is pivoted on the drive shaft 54 by the drive lever 56 as the fixed-throw crank 58 is rotated by the drive motor. The nozzles 34, therefore, reciprocate in alignment with each other from the plane 25 with the water jets from the respective nozzles moving transversely over the surface of a log passing through the debarking station.

To completely debark a log in this manner it is imperative that the water jets sweep across the entire surface of the log from top to bottom and vice versa. It is also important that the amount of jet overtravel be minimized to keep water loss low and thereby increase efficiency. This is accomplished by a simple, accurate and reliable control mechanism which will now be described.

The means for controlling the operation of the debarking nozzles responsive to logs of various sizes (Figs. 3, 5 and 6) includes the baffle 28 which serves as a log-diameter-sensing element to automatically adjust the amplitude of the reciprocal movement of the nozzles from the fixed plane 25, the spacing of the nozzles on either side of the log, the speed of log travel and the speed of nozzle travel. As logs of various sizes are conveyed past the debarking station the free end of baffle 28 which rides on the top surface of the logs will move up and down depending on the diameter of the logs. Movement of the baffle 28 is transmitted to the crosshead 61 slidably mounted on the drive lever 56 by a linkage mechanism (Fig. 3) comprising a shaft 78 on which the baffle 28 is mounted, a crank 80, connecting arm 82, crank 84, shaft 86, crank 88, and link 90 connected to a control piston rod 92 of a pneumatic servo cylinder 93. An upward swing of the baffle 28 will move the control rod 92 of servo cylinder 93 downwardly causing a power piston rod 94 of the servo cylinder to move downwardly. Downward movement of the piston 94 will rotate a shaft 96 through a crank 98 which will in turn actuate an adjusting rocker arm 100 on the shaft 72 by means of a crank 102 (on the shaft 96) and connecting link 104. The adjusting arm 100 mounted on the shaft 72 will slide the crosshead 61 up and down (towards and away from the drive shaft 54) on the drive lever 56 in response to movement of the baffle 28. In the example given, an upward swing of the baffle 28 as it rides up on a log of increased diameter will cause the crosshead 61 to slide up on the drive lever 56 to a point closer to the axis of drive lever 56.

As clearly shown in Figs. 5 and 6, the position of crosshead 61 on the drive lever 56 will determine the amplitude of the nozzle stroke from a substantially stationary base point (plane 25). Fig. 5 shows the crosshead 61 on the drive arm 56 in a position for debarking a thick log. The solid lines of Fig. 5 show the position of the parts when the nozzles are at the lowermost point in the reciprocal movement thereof. The dotted lines (Fig. 5) show the position of lever arms 48 and 50 after the crank 58 has been rotated from the solid-line position to a point near the top of the nozzle stroke. Fig. 6 shows the crosshead 61 on the drive arm 56 in a position for debarking a thin log. The solid lines of Fig. 6 show the position of the parts when the nozzles are at the lowermost point in the reciprocal movement thereof. The dotted lines (Fig. 6) show the position of lever arms 48 and 50 after the crank 58 has been rotated from the solid-line position to a point (corresponding to that shown in Fig. 5) near the top of the nozzle stroke. It is noted that the solid-line positions of the lever arms 48 and 50 in both Figs. 5 and 6 are substantially the same even though the position of crosshead 61 on the drive lever 56 is at the two extremes of adjustment. A comparison of the dotted-line positions of lever arms 48 and 50 in Figs. 5 and 6 clearly demonstrates the difference in the height or amplitude of nozzle stroke as the crosshead 61 is slidably adjusted on the drive lever 56 in response to variations in diameter of logs passing under the baffle 28.

The substantially constant lowermost point of nozzle travel (plane 25) is maintained throughout the range of adjustment of the crosshead 61 on the drive lever 56 by the particular construction of the drive mechanism employed. As shown in Figs. 5 and 6 an arc 105 described by rotating the connecting rod 60 about its pivotal connection to the fixed-throw crank 58 in the solid-line positions shown will intersect the longitudinal axis 107 of drive lever 56 at two points which represent the positions of crosshead 61 on the drive lever 56 at either end of its range of adjustment. The amount of error (variation from plane 25) of the base point of nozzle stroke in all positions of the crosshead 61 will vary with the length of connecting arm 60. The longer the arm the less the resulting error.

Simultaneously with the adjustment of the amplitude of nozzle stroke in the manner previously described, the horizontal spacing of the nozzles on either side of a log will be correspondingly adjusted to accommodate logs of various diameters. The guideways 46 are slidably mounted on either side of the debarking station on triangular rods 106 and are movable in response to movement of the baffle 28. As previously explained, movement of the baffle 28 will rotate the shaft 96. Rotation of the shaft 96 will slide the guideways 46 (Fig. 3) by means of a crank 108, connecting arm 110, crank 112, shaft 114 and double-throw crank 116 pivotally connected at one end to the guideway on the right by a link 118 and pivotally connected at the other end to the left-hand guideway by a connecting arm 120. When the baffle 28, for example, is swung upwardly in response to a log of increased diameter the position of guideway 46 will be automatically adjusted outwardly away from the path of log travel simultaneously with the adjustment of nozzle-stroke amplitude (increase) in the manner previously described.

Since the conveying mechanism 13 and the mechanism for actuating the nozzles are driven from a common drive shaft (shaft 21) the amount of longitudinal travel of a log past the debarking station for each complete stroke of the nozzles will remain constant no matter at what speed the shaft 21 is driven by the motor 19. It is desirable that the speed of nozzle travel be maintained at a constant predetermined speed for proper debarking of the logs. It is noted in this connection that if the speed of shaft 21 remains constant the nozzle-travel speed will increase when the amplitude of nozzle stroke is increased. To compensate for this variation in nozzle speed due to

the variations in nozzle stroke amplitude, a speed-control mechanism is employed which will vary the speed of drive shaft 21 in response to changes in log diameter. This mechanism (Fig. 1) includes a crank 122 mounted on an end of the shaft 78 which carries the baffle 28, which actuates the variable-speed transmission 20 through a connecting arm 130, bell crank 132, connecting arm 134, bell crank 136, and connecting arm 138 pivotally connected to a lever 140 which actuates the variable-speed transmission 20. Therefore, when the baffle 28 is swung upwardly in response to a log of larger diameter the control mechanism just described will actuate the variable-speed transmission to reduce the speed of drive shaft 21 and thereby maintain the nozzle-speed travel at a predetermined speed.

A brief summary of the operation of the device is as follows:

A log 12 is introduced into the machine (Fig. 2) and is translated longitudinally from right to left along the fixed plane 25 by the conveying mechanism 13. The log will contact the baffle 30 which serves to hold the log in a stable position and will then contact the baffle 28 which will slide up on the top surface thereof and automatically adjust the amplitude of nozzle stroke so that the jets from the nozzles will move transversely of the log from the plane 25 at the bottom thereof up to the top of the log. The baffle 28 will also position the nozzles with respect to the sides of the log at the proper distance therefrom. The speed of log travel and also the speed of nozzle travel will be adjusted in accordance with the position of baffle 28 to maintain a predetermined nozzle speed. As log 12 passes the debarking station 10 and is followed by a log 14 of smaller diameter the baffle 28 will move down from the thicker log 12 to the top surface of the thinner log 14, as shown in Fig. 2. This repositioning of baffle 28 will automatically reduce the amplitude of nozzle stroke to correspond to the diameter of log 14 and the spacing of the nozzles will also be adjusted inwardly closer to log 14. The speed of log travel will be increased so as to maintain the same speed of nozzle travel notwithstanding the decrease in the amplitude of nozzle stroke.

We claim:

1. A hydraulic log-debarking apparatus of the type in which logs of various diameters are translated longitudinally along a fixed plane comprising, a frame having a debarking station, a pair of spaced oppositely facing nozzles movably mounted on said frame at said station on opposite sides of logs passing therethrough, means for feeding liquid under pressure to said nozzles, actuating means for imparting reciprocable straight-line movement to said nozzles from said fixed plane so that the jets of liquid from said nozzles will move transversely over the surface of a log passing through said station, and control means for said actuating means including a log-diameter-sensing element to automatically adjust the amplitude of the reciprocal movement of said nozzles from said fixed plane.

2. A hydraulic log-debarking apparatus according to claim 1 in which said actuating means includes a cross-head slidably mounted in a guideway for each nozzle, said nozzles being fixedly mounted in said crossheads and said guideways being slidably mounted on said frame for movement toward and away from a log passing said debarking station.

3. A hydraulic log-debarking apparatus according to claim 1 in which said actuating means includes a drive shaft rotatably mounted on said frame, a drive lever fixedly mounted on said shaft, a fixed-throw crank operatively connected to said drive lever by a connecting rod to oscillate said drive lever and thereby pivot said drive shaft when said fixed-throw crank is rotated, said drive shaft being operatively connected to said nozzles to actuate said nozzles as said drive shaft is pivoted.

4. A hydraulic log-debarking apparatus according to claim 3 in which said control means includes a cross-

5 head slidably mounted on said drive lever and pivotally connected to said connecting rod, said crosshead being operatively connected to said log-diameter-sensing element and slidably thereby to vary the effective length of said drive lever acting on said drive shaft to thereby vary the stroke of said nozzles to accommodate logs of varying diameter.

5. A hydraulic log-debarking apparatus according to claim 4 in which the longitudinal axis of said drive lever, when said nozzles are at the end of a stroke at said fixed plane intersects an arc, that would be formed at that time if the pivotal connection of said crosshead to said connecting rod were rotated about the pivotal connection of said connecting rod to said fixed-throw crank, at two points 15 which represent the positions of the sliding crosshead on said drive lever at either end of its range of adjustment.

6. A hydraulic log-debarking apparatus of the type in which logs of various diameters are translated longitudinally along a fixed plane comprising, a frame having 20 a debarking station, a pair of spaced oppositely facing nozzles movably mounted on said frame at said station on opposite sides of logs passing therethrough, means for feeding liquid under pressure to said nozzles, actuating means for imparting reciprocable straight-line movement to said nozzles from said fixed plane so that the jets of liquid from said nozzles will move transversely over the surface of a log passing through said station, and control means for said actuating means including a log-diameter-sensing element to automatically adjust the spacing of 25 said nozzles.

7. A hydraulic log-debarking apparatus of the type in which logs of various diameters are translated longitudinally along a fixed plane comprising, a frame having a debarking station, a pair of spaced oppositely facing nozzles movably mounted on said frame at said station on opposite sides of logs passing therethrough, means for feeding liquid under pressure to said nozzles, actuating means for imparting reciprocable straight-line movement to said nozzles from said fixed plane so that the jets of liquid from said nozzles will move transversely over the surface of a log passing through said station, and control means for said actuating means including a log-diameter-sensing element to automatically adjust the amplitude of the reciprocal movement of said nozzles from said fixed plane and the spacing of said nozzles.

8. A hydraulic log-debarking apparatus of the type in which logs of various diameters are translated longitudinally along a fixed plane comprising, a frame having a debarking station, a pair of spaced oppositely facing nozzles movably mounted on said frame at said station on opposite sides of logs passing therethrough, means for feeding liquid under pressure to said nozzles, actuating means for imparting reciprocable straight-line movement to said nozzles from said fixed plane so that the jets of liquid from said nozzles will move transversely over the surface of a log passing through said station, and control means for said actuating means including a log-diameter-sensing element to automatically adjust the amplitude of the reciprocal movement of said nozzles from said fixed plane, the spacing of said nozzles, and the speed of log travel.

9. A hydraulic log-debarking apparatus of the type in which logs of various diameters are translated longitudinally along a fixed plane comprising, a frame having a debarking station, a pair of spaced oppositely facing nozzles movably mounted on said frame at said station on opposite sides of logs passing therethrough, means for feeding liquid under pressure to said nozzles, actuating means for imparting reciprocable straight-line movement to said nozzles from said fixed plane so that the jets of liquid from said nozzles will move transversely over the surface of a log passing through said station, and control means for said actuating means including a log-diameter-sensing element to automatically adjust the amplitude of the reciprocal movement of said nozzles from

said fixed plane, the spacing of said nozzles, the speed of log travel, and the speed of nozzle travel.

10. A hydraulic log-debarking apparatus having means for moving logs longitudinally along a path, a nozzle directed at a log on said means and reciprocally mounted for movement away from and back toward a fixed plane substantially tangent to said logs while remaining parallel to said plane, means for supplying water under high pressure to discharge through said nozzle, means controlled by the diameter of a log moving along said path to move said nozzle toward and away from such a log and to

10

5

change the amplitude of the reciprocal movement of said movement from said plane, and means controlled by the diameter of a log moving along said path to control the longitudinal speed of travel of such a log and the speed of the reciprocal travel of said nozzle.
